(57) CLAIM

The ornamental Design for a tire tread, as shown and described.

DESCRIPTION

FIG. 1 is a perspective view of a tire tread showing our new design, it being understood that the pattern repeats uniformly throughout the circumference of the tread; FIG. 2 is a front elevational view thereof; and, FIG. 3 is a right side elevational view thereof, the other side being a mirror image of the right side thereof.

In the drawings, the broken lines depicting the tire inner bead and sidewall and the peripheral boundary between the sidewall and inner bead are for illustrative purposes only and form no part of the claimed design. The dark stippled surface shading represents the recessed portion of the tread grooves, having a depth as best shown in FIG. 2.
